POLE CLOTHES RACK

Gregory M. Bucknam, Del Mar, Calif.
(714 Kennebeck Court, San Diego, Calif. 92109)

Filed Oct. 25, 1974, Ser. No. 346,466

Term of patent 14 years

Int. Cl. D6—99

U.S. Cl. D6—28

FIG. 1

FIG. 2

FIG. 1 is a view in side elevation of a pole clothes rack showing my design.

FIG. 2 is an opposite side elevation view from that of FIG. 1.

FIG. 3 is a view from the top thereof.

I claim:

The ornamental design for a pole clothes rack, as shown.
